US00D923292S

(12) **United States Design Patent** (10) **Patent No.:** **US D923,292 S**
(45) **Date of Patent:** **** Jun. 29, 2021**

(54) **MEDICAL GOWN**

(71) Applicant: **ALLEGIANCE CORPORATION**, Waukegan, IL (US)
(72) Inventors: **Joseph Angelo Palomo**, Fox Lake, IL (US); **Eric Dale Euteneuer**, Nevis, MN (US); **Lianhong Wang**, Singapore (SG); **Kyle Alexander Cushman**, Powell, OH (US); **Rogelio Reyes**, El Paso, TX (US); **Armando Quinonez**, El Paso, TX (US); **Stephen James Cox**, Gurnee, IL (US)

(73) Assignee: **Allegiance Corporation**, Waukegan, IL (US)

(**) Term: **15 Years**

(21) Appl. No.: **29/720,276**

(22) Filed: **Jan. 10, 2020**

Related U.S. Application Data

(62) Division of application No. 29/647,532, filed on May 14, 2018, now Pat. No. Des. 876,048.

(57) **CLAIM**

The ornamental design for a medical gown, as shown and described.

DESCRIPTION

FIG. 1 is a front perspective view of a medical gown; FIG. 2 is a front elevational view thereof;

FIG. 3 is rear elevational view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The broken lines shown illustrate portions of the medical gown that form no part of the claimed design.
